UNITED STATES PATENT OFFICE.

JEFFERSON McBRIDE SHARP, OF OIL CITY, PENNSYLVANIA, ASSIGNOR TO NATIONAL TRANSIT PUMP & MACHINE COMPANY, OF OIL CITY, PENNSYLVANIA, A CORPORATION OF PENNSYLVANIA.

ENGINE.

Application filed October 7, 1919. Serial No. 329,007.

To all whom it may concern:

Be it known that I, JEFFERSON McBRIDE SHARP, citizen of the United States, residing at Oil City, in the county of Venango and State of Pennsylvania, have invented 5 certain new and useful Improvements in Engines, of which the following is a specification.

The objects, construction and operation 10 of my improved engine are herein set forth with sufficient clearness to enable those skilled in the respective arts of constructing and operating steam and other fluid-actuated engines to make and use the same.

15 One object of this invention is to provide a steam or fluid-actuated engine wherein the steam-valve will, in the main, be actuated by the steam or other actuating fluid employed to operate the engine. Another 20 object is, to provide a steam engine in which the desired cushioning action may be readily secured without the use of special valves for this purpose. Other objects will be disclosed in the following specification.

25 One form of construction whereby I attain said objects is clearly illustrated in the accompanying drawings, the various figures of which are as follows:

30 Fig. 1 is a side elevation of the cylinder and the mechanical valve-actuating gear.

Fig. 2 is an end elevation of said cylinder.

Fig. 3 is a plan view of the cylinder with the steam chest and valves removed to show the ports more clearly.

35 Fig. 4 is a vertical longitudinal section of the upper wall of the cylinder on line IV—IV of Fig. 3.

40 Fig. 5 is a vertical longitudinal section of the upper wall of the cylinder on line V—V of Fig. 3.

Fig. 6 is a central vertical longitudinal section through the power cylinder on line VI—VI of Fig. 3.

45 Fig. 7 is a vertical section through the upper portion of the power cylinder and the central line of the steam chest showing the slide valve in section and the valve-actuating piston in side elevation.

Fig. 8 is a plan view of the slide valve.

50 Fig. 9 is an end elevation of said valve.

Fig. 10 is a longitudinal section on line x—x of Fig. 8.

Fig. 11 is a transverse section on line xi—xi of Fig. 8.

Fig. 12 is an inverted plan view of said 55 valve showing the modified form of chamber.

Figs. 13 to 16 inclusive are plan views of the port face of the steam chest, showing 60 the slide valve in its four principal positions.

It should be understood that these drawings are merely intended for the purpose of clearly illustrating one form of mechanical embodiment of my inventive idea; one 65 which has been found in actual practice to be productive of economy, efficiency, and smoothness of operation, but inasmuch as modifications of considerable variation 70 from the construction shown, could be employed without departing from the scope of my inventive idea, it is not my intention to be limited to the precise construction 75 shown in the drawings.

Before entering upon a description in detail of the construction, as illustrated, a general statement of the predominating points of my invention will be conducive to a clear fundamental conception of same.

80 A slide valve is employed in the steam chest to co-operate with the ports for the admission and release of the steam or other actuating fluid to the bore of the cylinder and this valve is adapted to have four distinct movements for each cycle of the engine; two of these movements are substantially parallel to the axis of the cylinder, or in the same directions as the movements of 85 the power piston: these movements I have termed pilot movements and are communicated to the slide valve, mechanically, by 90 means of gearing connected to the piston rod.

95 The two other movements of said valve are transversely to the axis of the cylinder, and are communicated to the slide valve by a fluid-actuated piston. These four movements are communicated to the slide-valve in such order and sequence that it is caused 100 at each cycle of the engine to describe a rectangle, which may at times vary to a rhomboid, depending upon certain adjustments of the gearing aforesaid.

105 Said four movements of the slide-valve cause the same to co-operate with and control the steam-chest ports of the separate steam-admission passages for each end of the power cylinder and also to effect

communication between these ports and the port of the exhaust passage, whereby steam is released from the cylinder.

The slide valve which I employ is of the well-known D-type, the cavity or chamber of which is modified,—as hereafter fully explained—so as to adapt it to perform the functions due to the four positions to which it is successively actuated.

10 It is the provision of the two separate steam-admission passages for each end of the cylinder, the relative location of the ports for these passages in the cylinder bore, the arrangements of the ports of these 15 passages in the steam-chest with relation to each other and to the port of the exhaust passage together with the construction and operation of a single valve to properly co-operate with and control these ports for the 20 admission and release of the piston-actuating fluid, and to secure the proper cushioning action thereby, which form the essential features of my invention. I am aware that 25 direct acting engines have heretofore been constructed which employ two valves for the accomplishment of substantially the same objects and functions above mentioned, but, so far as I am aware, these functions have not heretofore been accomplished by 30 means of a single valve.

The construction, as illustrated by the drawings, is substantially as follows:

The bore 1 of the working-cylinder 2 is 35 provided with a piston 3 which may be of the usual construction; said piston is provided with a rod 4 which extends through a stuffing-box 5 in the cylinder-head 6. Said cylinder 2 is provided with a steam-chest-seat 7, which carries the steam-chest 8.

40 Within said steam-chest is located a slide-valve 9 which is adapted to have a movement in a line parallel with the axis of cylinder; said valve 9 is actuated by means of a stem 10, which is connected to the upper end of the lever 11 by means of the valve-stem-link 10', which lever is provided with a fulcrum 12 in the sleeve or collar 13, that is carried by a tie-rod 14 which serves to connect said cylinder 2, to any other suitable appliance 45 to be operated, such as a pump (not shown); the lower end of lever 13 is connected to the piston-rod 4 through a link 15', and arms 15, that are carried by the split cross-head 16, which is secured to said piston-rod by 50 means of the bolts 17. The upper end of said lever 11 carries an eye-block 18 which is easily slidable upon said valve-stem-link 10'. Tappets 19 and 20 are mounted upon said valve-stem-link 10' by means of a 55 screw-thread, whereby adjustability is provided to secure a greater or lesser degree of actuation of said stem by said eye-block as the same contacts with said tappets 60 respectively, and thus to actuate said stem and the thereto connected slide-valve 9.

Various views of said valve 9 are shown in Figs. 8 to 12 and by a reference to Figs. 8, 9, 10, and 11 it will be noticed that said valve is provided with two actuation lugs 22, 22 between which an actuation-block 22' is located, and which is secured to said stem 10 by means of a pin 23. An elongated slot 24 is provided through said lugs 22 for the passage of said stem 10, whereby a movement of said valve, transversely to the movement imparted by said stem 10 and block 22' is provided for.

For the purpose of effecting said transverse movement of valve 9, a piston 25 is provided, which is carried in a suitably constructed cylindrical casing 26 located above the steam-chest. The respective ends of said piston are formed into a head or piston 27 and 28, which are united by a neck 29. The inner opposing faces 30, 30 of said heads are adapted to bear upon the end faces 31—31 of the lugs 22, for the purpose of actuating said valve 9. The respective piston-heads 27 and 28 fit closely in the cylindrical casing provided therefor, thus adapting said piston to be fluid-actuated.

The manner in which said fluid-actuation is attained will presently be pointed out, but this will be more easily understood if the various admission and release passages and the relative arrangement of the ports thereof are first explained.

Referring to Figs. 3, 4, 5, 6 and 13, it will be noted that there is an admission-passage for each end of the cylinder, as 32 and 33 respectively, and that these passages are located at and extend parallel with the longitudinal center line of the cylinder; the steam-chest ports 34 and 35 of these passages are positioned adjacent to the ends of the steam-chest; the cylinder ports 37 and 38 of these passages are located at the extreme ends of the cylinder and are positioned in the counterbore, so that they are never covered or controlled by the piston 3. From the passage 35 a steam-duct 39 leads to one end of the bore of the piston casing 26: from the passage 34 a steam-duct 40 leads to the bore at the opposite end of the 105 said piston casing.

The steam-inlet to the steam-chest is indicated by the reference numeral 41.

Located between the ports 34 and 35 is the release or exhaust port 42. Upon either side of said exhaust port is located the main admission ports 43—44. Port 43 opens into the passage 45 which leads to one end of the cylinder; the cylinder port 47 of this passage is located farther from the end 110 of the cylinder than the port 37, so that it is covered by the piston 3 when said piston is at the extreme of the stroke in this end of the cylinder.

Port 44 opens into a passage 46 which 115 leads to the other end of the cylinder; the

cylinder port of this passage is also located farther from the end of the cylinder than port 38, so that it is also covered by the piston at the interval when the piston is at 5 this extreme end of its stroke.

In Figs. 4 and 5 the piston 3 is shown in dotted lines for the purpose of indicating its position with reference to said ports 47 and 48 as just stated; these respective positions of the piston should not, however, be considered in connection with the explanation which immediately follows.

Reverting now to the actuations and functions of the slide-valve 9, they are as 15 follows:

Referring to Fig. 13, note that the position of the slide-valve is shown by the shaded section,—which is also the case in Figs. 14, 15, and 16. It may now be readily 20 understood that inasmuch as live steam is being admitted at port 41, this steam fills the steam-chest and is free to pass through port 44, passage 46, and port 48 (Fig. 5) into one end of the cylinder; steam may also 25 pass through port 34, passage 32 and port 38 into the same end of the cylinder. Steam is also being released from the opposite end of the cylinder port 47, passage 45, port 43, and the exhaust port 42. Also at this 30 juncture steam is being admitted through duct 40 to one end of the valve-actuating piston 25. The next position of the slide-valve is shown in Fig. 14, which indicates that said valve has been actuated longitudinally by the valve stem 10 so as to release steam through port 34, and admit steam to the opposite end of the cylinder through port 35. This movement of the valve is what is termed a "pilot" movement, since its 35 function is to admit steam to and release it from the piston casing, whereby said piston-valve is caused to move transversely and to shift the slide-valve 9 across the ports 43 and 44.

45 Note that in said Fig. 14 steam may pass to one end of the valve-actuating piston through the duct 39, and be released from the other end of said valve through the duct 40. This causes an actuation of said 50 valve-actuating piston which is communicated to the slide-valve and shifts it transversely to the position shown in Fig. 16, in which steam may be admitted to one end of the cylinder through port 43, passage 45 and port 47; steam may also be released from the opposite end of the cylinder through port 48, passage 46, port 44, and the exhaust port 42.—The next actuation 55 from the position shown in Fig. 16, is a longitudinal actuation to cause another pilot function of the slide-valve; this position is shown in Fig. 15, and completes the cycle of operation.

60 A steam cushion is formed at the end of each stroke of the piston 3 in the follow-

ing manner. By a reference to Fig. 4 it will be seen that the piston 3 when at one extreme end of the stroke covers the port 47, and at this juncture port 35 is also covered by the slide-valve 9; there being, 70 therefore, no further release or escape for the steam, it is compressed and forms an efficient cushion to arrest the momentum of the piston prior to the reversal of its movement. High speed is therefore attainable with this construction.

75 Attention is now directed to Fig. 12 of the drawings, which is an inverted plan view of the slide-valve.

80 From the foregoing description of the functions of this valve, the object of the diagonal lines *a—a* of the valve will readily appear, which is to cause the valve, upon its transverse movements to close the ports 35 and 34, as shown in Figs. 13 and 16 respectively.

85 From the foregoing description it will readily be noted that I am enabled, by means of a simple rectilineally movable slide valve of the D-type, to secure certain objects 90 which heretofore have been secured only by means of oscillating, cylindrical pistons, or pistons operating in a cylindrical chamber; such pistons are not only difficult and expensive to construct, but, unlike valves of 95 the D-type, they are unable to "follow up their own wear" and when they become slightly worn they must be renewed, and the cylindrical chamber in which they operate must be rebored in order to secure the 100 original efficiency. Furthermore, all rotative valves are liable to stick, either from expansion due to heat, or from rust, and are therefore unreliable, expensive to operate, and difficult to keep in repair. A valve 105 of the D-type is not subject to any of these objections, and all engineers and operatives are familiar with its construction and operation.

110 From an inspection of the inverted plan view, Fig. 12, it will readily be noted that the chamber or exhaust cavity of the valve 9, as defined at the seating face of said valve, has a substantially rhomboidal form: This particular form is for the purpose of adapting said valve to control the ports 34 and 35. The function of said valve, relative to the ports 42, 43 and 44, is affected by its 115 relatively transverse movement only,—that is, the movement caused by the valve-actuating piston: whereas the functions of said valve 9 in relation to said ports 34 and 35, are affected by both its longitudinal and transverse movements, as will be noted by a reference to Figs. 13, 14, 15 and 16.

120 I claim the following:

125 1. A single cylinder engine comprising in combination, a power cylinder, a piston operative in the bore of said cylinder, said cylinder being provided with a plurality of 130

steam passages leading to the same end of said cylinder, each of said passages having a port communicating with the bore of said cylinder, said ports being differently positioned as to their proximity to the end wall of said bore, said cylinder being also provided with a single release passage; a steam chest carried by said cylinder with which all of said passages communicate, 10 each through its individual port, a single valve of the D type adapted by movement in four directions to co-operate with and to govern all of said steam chest ports for the admission of steam to said steam passages and the release of same from all of them into said release passage as and for the purpose set forth, and means arranged to actuate said valve accordingly, said means including a stem connected directly 20 to said valve to which stem movement is transmitted by suitable intermediate mechanism from the rod of said piston, also a steam-actuated piston operably connected to said valve so as to actuate same in a plane transversely to the actuation of said stem.

2. A single cylinder engine comprising in combination, a power cylinder, a piston operative in said cylinder provided with the usual piston-rod, a steam chest carried by 30 said cylinder, two primary steam passages leading respectively from said steam chest into the opposite ends of the bore of said cylinder, the port which opens from each of said passages into said bore being positioned so as to be covered by the piston when at the respective extremes of its stroke, two secondary steam passages leading respectively into opposite ends of the bore of said cylinder, the ports which open from 40 said secondary passages into said bore being positioned at the extreme ends of said bore respectively so as not to be covered by said piston when at the respective extremes of its stroke, an exhaust passage leading 45 from said steam chest to the atmosphere, a rectilineally-movable valve of the D type operable to effect the admission of steam from said steam chest into the bore of said cylinder through said steam passage and the release of same from said primary passage, also the partial release of same from said secondary passage through said exhaust passage, and means actuating said valve accordingly which means includes a longitudinally-reciprocating stem connected to said valve, actuated through suitable intermediate mechanism from said piston rod and in alinement therewith, also a steam-actuated piston operably connected to said valve so as to actuate same in a plane transversely to the actuation of said stem.

3. In an engine in combination, a power cylinder, a power piston operative in said cylinder, a steam-chest carried by said cylinder, two primary steam passages leading

from said steam-chest to opposite ends of said cylinder respectively, each provided with a port leading into the bore of said cylinder, said ports being positioned so as to be covered by said piston when at the respective extremes of its stroke; two secondary steam passages leading from said steam-chest into the counter-bore of said cylinder, a release passage said passages being provided each with a port communicating with said steam-chest, said steam passages being also communicable with said release passages; a valve of the D type in said steam-chest adapted to co-operate with and to govern all of said ports for the purposes set forth, and means for actuating said valve, comprising a valve stem operably connected to said power piston, and a steam-actuated piston also operably connected to said valve, the steam-actuation for said last-mentioned piston being controlled by said valve.

4. In an engine, in combination, a power cylinder provided with a steam chest, and having a plurality of steam passages leading from said chest to the same end of the bore of said cylinder, each through its respective port in said chest and said cylinder, said cylinder ports varying as to their location longitudinally of the cylinder-bore, a release port in said steam chest co-operative with all said other ports therein, a slide valve of the D type governing all of said steam chest ports, means for actuating said valve accordingly comprising a valve-stem connected to a suitably-operative element of the engine, and a steam-actuated piston, steam for the actuation of which is controlled by said valve, and a piston operative in said cylinder, adapted to co-operate with the cylinder-port of one of said passages, for the purpose set forth.

5. In an engine, in combination, a cylinder provided with a steam chest and having a plurality of steam passages leading from said chest to the same end of the bore of said cylinder, each through its respective port in said chest and said cylinder, said cylinder ports varying as to their location longitudinally of the cylinder bore, a release port in said steam chest co-operative with all said other ports therein, a slide valve of the D type having a chamber of a substantially rhomboidal form, whereby, conjointly with the various positions assumed during the movements of said valve, it is adapted to co-operate with and govern all of said steam chest ports, means for actuating said valve accordingly, and a piston operative in said cylinder and overrunning one of said cylinder ports for the purpose set forth.

6. In an engine, in combination, a power cylinder, a steam chest carried by said cylinder, said cylinder being provided with two steam passages leading through separate ports from said steam chest to the same end

- of the bore of said cylinder, and each communicating with said bore by means of a port, one of which ports is positioned within the limit of travel of the power piston, 5 the other of said ports being positioned beyond said limit of travel, a release port for said steam chest adapted for co-operation with said other ports of the steam chest, a slide valve of the D type having an exhaust 10 chamber of substantially rhomboidal form whereby it is adapted to govern all of said steam chest ports for the purposes set forth, which includes the closure of one of the ports to produce a final cushioning of the power 15 piston as one of said purposes, means for actuating said valve comprising a suitably-actuated valve stem and a steam-actuated piston operably connected to said valve, steam for the actuation of said last-mentioned piston 20 ton being controlled by said valve, and a piston operative in said power cylinder overrunning said port which is positioned within in said limit of its travel.
7. In an engine, in combination, a power 25 cylinder, a piston operative therein and provided with the usual piston-rod, a steam chest carried by said cylinder, two steam passages leading through separate ports in said steam chest to the same end of 30 the bore of said cylinder and communicating therewith through separate ports, one of which is positioned to be overlapped by said piston at the end of its stroke, the other of said ports being positioned at the extreme end of said cylinder 35 so as not to be overrun by said piston, a valve of the D type having a chamber which, upon the valve face, is substantially rhomboidal in form, carried in said steam chest 40 and adapted to have two relatively transverse movements whereby and in conjunction with said rhomboidal form of its chamber it is adapted to govern the admission of steam to said cylinder and the release of 45 same therefrom through all of said passages, means actuated by said piston for transmitting one of said movements to said valve, and a steam-actuated, longitudinal movable piston adapted to transmit said 50 other movement to said valve, the steam for the actuation of said last-mentioned piston being controlled by said valve.
8. An engine comprising, in combination, a power cylinder, a piston operative in said cylinder and provided with the usual piston-rod, a steam chest carried by said cylinder, a primary steam passage leading from a port in said steam chest to a port adjacent to one end of the bore of said cylinder positioned so as to be overlapped and closed by said piston at the related end of its stroke, a secondary steam passage leading from a port in said steam chest to a secondary port in the bore of said cylinder positioned so as not to be closed by said piston, a release port in said steam chest, a valve of the D type in said steam chest having two movements relatively transverse each to the other controlling all of said steam chest ports as and for the various 70 purposes set forth, a steam-actuated, longitudinally-movable, valve-actuating piston mounted in proximity to said slide valve operably connected thereto so as to move the same in one of said directions, means for alternately admitting steam to and releasing same from the respective ends of said actuating piston to cause said piston-actuation, and means operably connected to said piston-rod for actuating said valve in 75 said other direction.
9. In an engine, the combination of a power piston and a controlling valve for the actuating medium for said piston, actuating means for said valve consisting of a mechanically actuated stem operably connected to said valve, a fluid-actuated piston also connected to said valve, the actuating fluid for said last-mentioned piston being controlled by said valve; said power piston and said valve being adapted and co-operating to produce a cushioning of said power piston at the end of its stroke.
- In testimony whereof I affix my signature in presence of two witnesses. 95
